UNITED STATES PATENT OFFICE.

MICHAEL TAIN, OF SOUTH BOSTON, MASSACHUSETTS.

IMPROVEMENT IN PANTALOON-TREES.

Specification forming part of Letters Patent No. 140,172, dated June 24, 1873; application filed May 8, 1873.

To all whom it may concern:

Be it known that I, MICHAEL TAIN, of South Boston, in the county of Suffolk and State of Massachusetts, have invented certain Improvements in Boards for Stretching the Legs of Pantaloons, of which the following is a full, clear, and exact description, reference being had to the accompanying drawings making part of this specification, in which—

Figure 1 is a perspective view of the front portion of a stretching-board, with my improvements applied thereto. Fig. 2 is a perspective view of the rear portion of a stretching-board. Fig. 3 is a perspective view of the wedge-shaped piece made to fit between the portions of the stretching-board shown in Figs. 1 and 2. Fig. 4 is a horizontal section through a pressing-board having my improvements applied thereto, and placed within the leg of a pair of pantaloons.

Boards, used by pressmen for stretching the legs of pantaloons, as at present constructed, are objectionable, for the following reason: The front piece of the board, at or near its lower end, has been made smooth, and when the lower part of the leg of the pants was stretched thereon it would not remain in place when the iron was applied thereto, the tendency being to slip up from the projecting portion at the lower end of the front, and resulting in the pants being wrinkled at this point.

My invention has, for its object, to overcome this difficulty, and consists in providing the lower portion of the front of the stretching-board with a roughened surface, or with points or projections which serve to hold the front of the lower portion of the leg of the pants without slipping, while the pressing-iron is applied thereto, by which means the spring-bottom or desired "set-off" is given without any wrinkles being produced.

To enable others skilled in the art to understand and use my invention, I will proceed to describe the manner in which I have carried it out.

In the said drawings, A represents the front piece of the stretching-board, of the ordinary form, being that shown in Figs. 1 and 4. B represents the rear piece of the board, and C the wedge-shaped piece, also of the ordinary form, the inner edges of the front and rear pieces A B being provided with grooves *a b* for the reception of a tongue, *c*, projecting from each edge of the wedge-shaped piece C, by means of which the pieces A and B of the board are pressed out against the inside of the leg of the pants. The surface of the front edge of the portion A between 5 and 6 swells out, and is provided with a series of points or projections *d*, which catch against the inside of the pants at and near the bottom where the spring or "set-off" is to be formed, by which means this portion of the leg of the pants, when placed upon the stretching-board, is prevented from slipping up and wrinkling, as was the case when the ordinary stretching-board was employed, having the surface of its front piece smooth from 5 to 6. By covering the lower portion of the pieces A B and wedge C with metal, I am enabled to prevent the adhesion of the pants to the board, which usually takes place where it is made of wood, when the pants are sponged previous to being pressed.

I am aware that a stretching-board, composed of two separate pieces, with a wedge introduced between them, by which they are spread apart, has been used; I therefore lay no claim to a board so constructed; but what I do claim as my invention, and desire to secure by Letters Patent, is—

The piece A having the lower or projecting portion of its front roughened or provided with points or projections, substantially as and for the purpose set forth.

Witness my hand this 3d day of May, 1873.

MICHAEL TAIN.
